UNITED STATES PATENT OFFICE.

ANTON LOHER, OF QUINCY, ILLINOIS.

HORSE-COLLAR.

SPECIFICATION forming part of Letters Patent No. 361,881, dated April 26, 1887.

Application filed February 12, 1887. Serial No. 227,403. (No model.)

To all whom it may concern:

Be it known that I, ANTON LOHER, of Quincy, in the county of Adams and State of Illinois, have invented certain new and useful Improvements in Horse-Collars; and I hereby declare the following to be a full, clear, and exact description of the same, reference being had to the accompanying drawings, forming a part of this specification, and to the figures and letters of reference marked thereon.

The object of my invention is to improve that class of leather horse-collars in which the shoulder-pads do not extend beneath the throat of the animal; and the said invention consists in the novel features hereinafter described, and pointed out in the claims.

In the accompanying drawings, Figure 1 is a perspective view showing the arrangement of the various parts. Fig. 2 is a view showing the lower ends of the two outside pad-covers. Fig. 3 is a cross-section on the line $\alpha\alpha$, Fig. 1. Fig. 4 shows the manner of stitching the fore-wale and pads together.

Similar letters of reference in the figures indicate the same parts.

A represents the fore-wale of the collar, which in my construction overlies all the other parts.

B B are the inner covers of the shoulder-pads, and C C' the outer covers of same, the cover C' being cut with the extension D, as will be presently explained. As in ordinary collars of this class the stuffing in the shoulder-pads does not extend under the throat, while the stuffing a of the fore-wale A extends entirely around the collar.

The outer cover, C', of one of the shoulder-pads is formed in any preferred shape until the throat portion is reached, where it is widened, preferably, into the shape shown at D, Fig. 2. The other cover, C, is attached to the end of the cover C' by means of a rivet, b, or other suitable means, and the widened portion D is then bent back over the throat portion and the ends of the inner pad-covers secured over it by a row or rows of stitching passed around their edges and straight across the said portion D. As an additional safeguard, and for greater strength, a row of stitching is passed through the ends near the outer edges of the outside pad-covers, as shown at e, Fig. 1. Having put these parts together,

the fore-wale A is applied with its edges overlapping the inner edges of all the pad-covers and the portion D, and is secured in this position by means of a suitable row of stitching, d, preferably of leather thong, passing through it.

By reference now to Fig. 4 it will be seen that the row of stitching d makes a very narrow seam on the inside of the collar, where only a very small portion of the stitches are exposed, while on the outside they are exposed in a relatively long diagonal stitch. The result of thus stitching the fore-wale and shoulder-pads together is to form a practically smooth collar on the inside, with a very narrow depression for the seam, and on the outside a wide depression for the hame-space.

From this description it will be seen that my collar is formed of comparatively few parts, the doubling of the outside pad-cover upon itself doing away with the necessity of employing a separate piece of leather to cover the seams in this portion of the collar, and also doing away with the row of stitching along the edge, at the same time presenting a smooth and elastic surface for the throat of the animal to bear against and to prevent the slipping of the hame-fastening.

It is obvious that any of the ordinary stiffening devices for the throat-section may be used in connection with my invention.

Having thus described my invention, what I claim as new, and desire to secure by Letters Patent, is—

1. In a horse-collar, the combination, with the fore-wale and shoulder-pads, of a row of stitching for uniting said parts, consisting of a thread or its equivalent passed back and forth through them, presenting on the outside of the collar a long diagonal stitch depressing a comparatively wide space, and on the inside a short stitch depressing a comparatively narrow space in the collar, substantially as described.

2. In a horse-collar, the combination, with the fore-wale and the shoulder-pads secured thereto, of the covers for said shoulder-pads, one of which is extended across from side to side of and widened at the throat portion of the collar, the widened portion being doubled upon itself, substantially as described.

3. In a horse-collar, the combination, with the fore-wale and the shoulder-pads secured thereto, extending down to but not across the

throat portion, of covers for said shoulder-pads, one of which extends across from side to side of and, in conjunction with the fore-wale, forms the throat portion of the collar, substantially as described.

4. In a horse-collar, the combination, with the fore-wale and the shoulder-pads secured thereto, of the covers for said shoulder-pads, one of which is extended across from side to

side of and widened at the throat portion, said widened portion being doubled upon itself and united to the opposite pad-cover by a rivet and rows of stitching or their equivalents, substantially as described.

ANTON LOHER.
